ELECTRIC INCANDESCENT LAMP

Wilhelm Honing and Justin Adrianus van der Kam, Eindhoven, Netherlands, assignors, by mesne assignments, to North American Philips Company, Inc., New York, N.Y., a corporation of Delaware

Application October 27, 1954, Serial No. 464,994

Claims priority, application Netherlands November 4, 1953

4 Claims. (Cl. 313—276)

This invention relates to a filament mounting structure for an electric incandescent lamp and has for its principle object to overcome the possibility of vaporized filament material deposited on the film carrier from short circuiting or otherwise causing a defect in the lamp.

According to the invention an incandescent lamp is provided in which a pair of spaced vertical carriers are mounted on a support and a pair of transverse insulated carriers are secured to the vertical carriers. A filament is suspended within the space defined by said carriers by securing means spaced from said transverse carriers and connected at one end to said filament and connected at the other end at a point on one of said transverse carriers located in a position remote from said filament.

As experience has shown, a very simple solution of the above-mentioned problem is thus obtained. Thus, in a preferred embodiment of a lamp according to the invention the securing means for attaching the transverse carrier to the vertical carriers are connected at one end to the vertical carrier and at the other to a point on the transverse carrier remote from said filament.

The cross-section of the said carrier may be shaped in many different forms. If the cross-section is circular it will in certain cases be preferable for this transverse carrier to have a groove recessed in it at its side more remote from the filament, in which groove the points at which the supporting wires emerge are arranged.

The invention will now be described with reference to the accompanying drawing in which:

Fig. 1 is a front elevational view of a projection lamp in which the filament is stretched in a plane;

Fig. 2 is a side view of the filament according to the invention partially in section and partially in elevation;

Figs. 3 and 4 are modifications of the device shown in Fig. 2, and

Fig. 5 shows the connection of the carriers according to the invention.

Referring now to Fig. 1, a lamp bulb 1 has vertically extending longitudinal carriers 2 with a U-shaped profile which at 3 terminates in current supply pins 4 which extends so as to project beyond the lamp. These current supply pins are sealed to a dish-shaped glass 5 to which the glass bulb 1 itself is sealed at the zone 6. The dish-shaped part 5 includes an exhaust tube at 7.

Between the vertically extending longitudinal carriers 2 transverse carriers 8 and 9 are arranged consisting of porcelain rods of circular cross-section. Metal wires 10 projecting from the end faces of transverse rods 8 and 9 are secured to the longitudinal carriers 2 by soldering. This results in a frame construction in which a filament 11 is stretched in zigzag. This filament shown in the embodiment of Fig. 1 consists of six members with its ends secured to the longitudinal carriers 2. The filament is maintained in the position shown by means of the securing means such as supporting hooks 12, 13, 14, 15 and 16. The supporting hooks 12 and 13 are secured to the transverse carrier 8, the supporting hooks 14, 15 and

2

16 to the transverse carrier 9. The supporting hooks 14, 15, 16 which consequently are secured to the transverse carrier 9 are directly inserted in the porcelain rod 9 at its side adjacent the filament. It is common practice to arrange the supporting hooks in the carrier arranged over the filament during operation of the lamp in the same manner. However, it is found that in this event a layer of vaporized filament material may settle on the side of such a carrier adjacent the filament, which layer extends between the points at which the supporting wires are inserted and consequently may give rise to breakdown or short-circuiting.

By now arranging the points at which the supporting hooks are inserted in the carrier 8 arranged over the filament during operation of the lamp at the side of this carrier more remote from the said filament, as is illustrated in Fig. 2, filament material which settles on the lower side of the carrier 8 is prevented from being brought into contact with the supporting hooks at which a potential is set up, with the result that the above-mentioned disadvantage is obviated or at least materially reduced.

As is shown in Fig. 2, the cross-section of the carrier 8 may be circular, while an end 12a of the supporting wire 12 is led around it describing a large curve and the point 13 at which the wire is inserted in the carrier 8 is arranged on its upper surface.

Fig. 3 shows an embodiment comprising a carrier 17 of triangular cross-section, the apex being turned down. Fig. 4 shows a carrier 18 of circular cross-section. It has a groove 19 recessed in it, in the base of which the supporting wires 21 are inserted.

In the embodiment shown in Fig. 5, which is a perspective view of a modified construction, use is made of a triangular transverse carrier 22 in the upper surface 35 of which not only the supporting hooks 23 and 24 but also the wire 25 joining the transverse carrier 22 to the longitudinal carrier 26 are inserted. Thus, a conductive layer is not likely to form between the points at which the wires 25 joining the transverse and longitudinal carrier are inserted. As may be seen from Fig. 5, the points at which the supporting hooks 23 and 24 are inserted in the upper surface of the carrier 22, are staggered.

While we have shown and described the preferred embodiment of our invention, it will be understood that the latter may be embodied otherwise than as herein specifically illustrated or described and that in the illustrated embodiment certain changes in the details of construction and in the arrangement of parts may be made without departing from the underlying idea or principle of the invention within the scope of the appended claims.

What is claimed is:

1. An electric incandescent lamp comprising a support, a pair of spaced longitudinal carriers mounted on said support, a pair of insulated, spaced, transverse carriers secured to said longitudinal carriers, a filament arranged within the space defined by said carriers, securing means for maintaining said filament taut and connected at one end to said filament and at the other end to one of said transverse carriers each of said securing means being fixed to a surface of said transverse carrier on the side thereof opposite to the side thereof facing said filament, said securing means approaching said transverse carrier from the side opposite to the side of securing of said securing means to said transverse carrier and bent around said carrier to the point of said securing.

2. An incandescent lamp as claimed in claim 1 in which said transverse carriers are connected to said longitudinal carriers by additional securing means connected at one end to said longitudinal carriers and at the other end to a surface on said transverse carriers located opposite to the surface facing said filament.

3. An incandescent lamp as claimed in claim 2 in which said transverse carriers are provided with a groove on a side opposite from the side facing said filament, and said securing means is connected at said other end in said groove.

4. An electric incandescent lamp comprising a support, a pair of spaced longitudinal carriers mounted on said support, a pair of insulated, spaced, inverted triangular transverse carriers secured to said longitudinal carriers, a filament arranged within the space defined by said carriers, wire securing means for maintaining said filament taut and connected at one end to said filament and at the other end to one of said transverse carriers at a point on the base of said triangular transverse carrier, each of said wire securing means being fixed to a surface 15 of said transverse carrier on the side thereof opposite to the side thereof facing said filament, said wire securing means approaching said transverse carrier from the side

opposite to the side of securing of said wire securing means to said transverse carrier and bent around said carrier to the point of said securing.
